UNITED STATES PATENT OFFICE.

DAVID C. KLAUSMEYER, OF CINCINNATI, OHIO, ASSIGNOR TO THE CINCINNATI BICK-FORD TOOL COMPANY, OF OAKLEY, CINCINNATI, OHIO, A CORPORATION OF OHIO.

SELF-INDICATING VARIABLE-SPINDLE DRIVE.

Application filed November 3, 1922. Serial No. 598,831.

To all whom it may concern:

Be it known that I, DAVID C. KLAUSMEYER, a citizen of the United States, and residing at Cincinnati, in the county of Hamilton and State of Ohio, have invented a new and Improved Self-Indicating Variable-Spindle Drive, of which the following specification is a full disclosure.

In a radial drilling machine, the drill-supporting spindle projects vertically downward; being journaled in a so-called head which is arranged to slide horizontally on an arm extending radially from a post. The spindle derives its motion from a splined shaft horizontally journaled in the radial arm; this motion being conveyed through suitable transmission means including speed change-gears which are usually located within the travelling head in which the spindle is journaled. The aforesaid change-gears are utilized for the purpose of determining the speed of rotation of the spindle, i. e. the ratio between the spindle and the aforesaid horizontal shaft that, in turn, derives its rate of rotation from a variable speed motor or from some other prime-mover through a primary speed-box adjustable to vary the rate.

For certain purposes, as for example for tapping, it is necessary that the motion (transmitted as above indicated) may be either forward or reverse in direction and, to accomplish that, it is usual to arrange a motion-reverser (as of the type of U. S. Patent 1,030,424) in that portion of the head which slides in proximity with the horizontal shaft; the parts being so constructed that, by swinging an appropriate lever, motion will be derived in the first instance from said horizontal shaft in either a forward or reverse direction.

In consequence of this conventional arrangement, the various change-gears in the spindle supporting head are caused to rotate in either one or the other direction according to the setting of the motion-reverser on the main shaft and this circumstance has led to a certain difficulty created by reason of the prevailing arrangement of the change-gears. That is to say, the change-gears have habitually included a gear of notable diameter which has heretofore been keyed to the spindle so as to rotate in unison with the spindle and at

whatever speed may be imparted to the spindle, whether it be the slow speed attained directly by means of said gear of notable diameter, or whether it be a more rapid speed produced by the flow of motion to another small gear also keyed to the spindle. The result of that conventional arrangement has been that, whenever the motion-reverser located on the main shaft has been operated to change the direction of transmission of motion, it is obliged to overcome the momentum of the aforesaid comparatively large gear which, by reason of being keyed at all times to the spindle, acts constantly as a species of fly-wheel irrespective of how the change-gears may have been otherwise intermeshed.

The immediate result on the motion-reverser of the aforesaid arrangement is that the motion-reverser is obliged to absorb considerable shocks when it is quickly actuated to effect a reversal of motion. For example, when the drill spindle is being used for tapping holes at a high rate of speed, and when thereupon the user throws the reversing lever to cause the tap quickly to be arrested before it gets too far into the hole and to cause it immediately to be reversed and hence rapidly withdrawn, the motion-reverser is necessarily subjected to considerable strains.

In such machines, the motion-reverser is habitually of the friction type; being necessarily so inasmuch as positive clutches would give rise to excessive shocks in arresting and reversing the moving parts. Much trouble has been experienced with the motion-reverser itself and, as a result of the long study that has been given this particular mechanism, motion-reversers for this particular purpose have been developed to a very high state of improvement. Even so, it still remains the source of much trouble inasmuch as the friction surfaces tend to wear unduly fast and the user of the conventional machine is therefore frequently put to the necessity of either readjusting the friction clutches or of replacing parts, as the case may be. It has been found, furthermore, with the steady growth in the size of the entire machine and the increased speeds at which it has become the practice to operate the drills, that more and more trouble is experienced with the mo-

tion-reverser in continuously performing its functions; notwithstanding every effort on the part of manufacturers to impart the highest degree of durability and reliability 5 to that mechanism.

The present invention is predicated upon the discernment that one of the reasons for the unduly rapid deterioration of the motion-reverser may be traced to an external 10 source. That is to say, while a certain amount of slipping is necessary and essential, (so that the changes in direction and speed may not be too abrupt) it is equally desirable that the friction-clutches should 15 not be compelled to overcome any more inertia than can reasonably be avoided. An excessive amount of slippage will, of course, very materially increase the normal wear of the friction-clutches and will unduly 20 shorten the serviceability of the motion-reverser. This is what happens in the case of the arrangement above-mentioned inasmuch as the fly-wheel gear is the indirect cause of an undue amount of wear in the 25 friction surfaces of the motion-reverser and the user of the machine is, as an indirect consequence, put to a great deal of trouble in re-adjusting and replacing certain parts of the friction-clutches.

30 One of the primary objects of this invention is therefore to accomplish a re-arrangement of the change-gears in such a manner that the momentum of the same will be low even when the spindle is being driven at its 35 high speed. In other words, by virtue of this invention, the large gear, which must be resorted to for driving the spindle at its low speeds, does not remain keyed to the spindle when the latter is driven at its high 40 speeds but is permitted to idle at its usual comparatively low speed notwithstanding the fact that the spindle itself may be operating at a relatively high speed.

45 It may also be observed that, while the drill-head habitually embodies a set of change-gears (usually yielding from two to four or more changes) there is included in the machine, as has been stated, another means for varying the speed (which may be 50 another set of change-gears which latter set is usually so located as to receive motion in the first instance from the prime-mover). These two sets of remotely located speed-change devices are arranged in series 55 (through intervening transmissions) and they cooperate to produce the total series of change available at the drill point. The speed-changer located near or constituting the prime-mover, as the case may be, customarily provides finer changes in ratio so 60 that the motion which flows therefrom and into and through the entire mechanism will not be too abruptly changed; whereas, the gear-set located in the drill-head (i. e., adjacent the drill point) usually is designed to

furnish coarser changes, inasmuch as comparatively few parts are affected by those last-mentioned changes. Furthermore, it is more convenient for the user to have within immediate reach the levers which effect the 70 coarser changes. Now, when a drilling operation is to be performed at a speed very close to the limit of capacity of the drill itself, it will be seen that the adjustment cannot be made with sufficient nicety by the 75 use of the coarser changes alone for the reason that a higher speed might exceed the capacity of the drill-point and a materially lower speed might not closely enough correspond to the maximum efficiency of the drill-point. Consequently, the attendant is put to the necessity of first adjusting what may be termed the secondary or coarser gear-set and of then adjusting what may be called 80 the primary or finer gear-set. Heretofore, this double adjustment has been accomplished by reference to certain tables or formulae and this has occasioned so much bother that the tendency of the workman is to ignore the table and adjust the different 85 gear-sets by guess or "rule of thumb"; all of which necessarily results in a sacrifice 90 of efficiency.

A further object of this invention is to 95 overcome this conventional difficulty by making it as simple as possible for the workman to determine the correct setting for the different sizes of drills and, to that end, this invention proposes a self-indicating instrumentality governed mutually by 100 the levers controlling the secondary gear-set in such a manner as to portray the adjustment to be independently made to the primary gear-set to satisfy the requirements of 105 the particular size of drill then mounted in the drill spindle. Thus, this arrangement places at all times before the immediate observation of the user the various settings that have been previously determined, by 110 elaborate efficiency tests, to be the ones best suitable for a particular size of drill and it prevents the ordinary workman from making mistakes; 1st, in improperly adjusting the secondary gear-set with respect to the 115 particular size of drill being employed and, 2nd, it enables him to graduate the coarser speed to the proper approximate point by indicating a correct independent adjustment for the primary gear.

120 Other objects and advantages will be in part indicated in the following description and in part rendered apparent therefrom in connection with the annexed drawings.

To enable others skilled in the art so 125 fully to apprehend the underlying features hereof that they may embody the same in the various ways contemplated by this invention, drawings depicting a preferred typical construction have been annexed as a part of this disclosure and, in such draw- 130

ings, like characters of reference denote corresponding parts throughout all the views, of which:—

Fig. 1 represents a vertical section of the improved head of a radial drill taken in a plane transverse to the longitudinal transmission shaft which is horizontally mounted on the usual radial arm. Fig. 2 is a fragmentary section taken in a horizontal plane showing a portion of one side of the casing of a head with the operating levers for re-arranging the change-gears mounted in the head. Fig. 3 is a fragmentary perspective of the side of the head showing the levers of Fig. 2 together with the self-indicating plates mutually controlled by said levers.

The general arrangement of a radial drill, being well known to those skilled in the art, requires no illustrations but, for convenience, reference may be made to United States Patent #1,374,581 for details of the column and sleeve construction including the transmission which derives its motion from a prime-mover located on the base of the machine near the foot of the column. Reference may likewise be made to U. S. Patent #1,024,220 for details of what may be referred to as a primary speed-change mechanism for imparting various rates of movement to the above-mentioned transmission. Reference may be made to U. S. Patents #883,118 and 1,204,668 and 1,204,684 for details concerning the radial arm, the spindle-supporting head, slideable thereon and the transmission and gearing for enabling the spindle to be driven by motion derived from the transmission elements mounted in the upright column and sleeve.

Referring now to the accompanying drawings, 1 indicates a portion of the radial arm and 2 denotes the splined shaft which is longitudinally journaled on said radial arm and 3 indicates one of the two conversely arranged bevel gears in mesh with the bevel gear 4 affixed to the lower end of the vertical shaft 5 journaled in bearings 6 and 7 provided by the frame 8 of the head which slides horizontally on the radial arm.

The gear 3 is one element of the frictional reverser that intervenes between the horizontal shaft 2 and the gear 4 to enable the latter to be driven in either direction; said frictional reverser being, for example, of the construction set forth in U. S. Patent, #1,030,424.

It will be understood from the foregoing explanation that the shaft 2 is subject to various changes in speed depending upon the adjustment of the speed-box or motor which, in the first instance, supplies power to the general mechanism.

Likewise journaled in bearings 9 and 10 in the frame 8 of the head, is a sleeve 11 in the bore of which is received the splined shank 12 of a spindle 13; an elongated key 14 serv-

ing to permit the spindle to be raised and lowered to force the drill into and out of the work while simultaneously causing the spindle to be rotated in unison with the sleeve 11. The means for rotating said sleeve by power transmitted from the shaft 5 will now be explained.

A duplex gear 15 is mounted on the shaft 5 so as to admit of being shifted thereon; the driving connection being established by a key 16 splined to the duplex gear 15.

The position of the latter is determined by a yoke 17 bearing against the sides of the larger gear 18 of the member 15. This gear 18, in one position of the member 15 is enabled to mesh with a gear 19 of the duplex gear keyed to an intermediate shaft 21 which, by means of bearings 22 and 23 is vertically journaled in the drill head. In its other position, the smaller gear 24 of the member 15 will engage the larger gear 25 of the member 20 so that, by this arrangement, the intermediate shaft 21 may receive motion at two different rates with respect to any given rate of rotation of the shaft 5.

The intermediate shaft 21 is provided with a pinion 26 which, in this embodiment, permanently meshes with a large gear 27 independently journaled on a bearing 28. The large gear 27 participates in the motion of the spindle 13 only when it is connected to function as a driver for said spindle as will be explained. In other words, the arrangement thus far described is such that the large gear 27 is utilized only for the purpose of rotating the spindle slowly and, when the spindle rotates rapidly, it does so independently of the large gear 27 since the latter never rotates more rapidly than at the rate determined by its intermesh with the small pinion 26 on the intermediate shaft 21.

Before proceeding to describe the further details of the gearing, attention is called to the fact that, by virtue of this peculiarity of construction, the operation of the frictional motion-reverser located between the shaft 2 and the gear 4 will never, so far as the gear 27 is concerned, impose upon either of the two friction clutches the necessity of overcoming any momentum in excess of the normal momentum of the slow running gear 27 since the latter does not exhibit the pronounced fly-wheel characteristics which it would occasionally have if connected to rotate in unison with the spindle when the latter was being driven at a high rate of speed by the mechanism now being explained.

The high speeds for the spindle are transmitted by the gear 29 affixed to the shaft 21. A gear-unit 30 is rotatable with the shaft 12 but is permitted to be shifted thereon by the spline 31; the shifting being accomplished by a shoe 32. By shifting the gear 30, its teeth 33 may be intermeshed with the

teeth 34 of the gear 29, thereby enabling the spindle to be driven at a high speed by reason of the fact that the gear 29 is materially larger in diameter than the pinion 26 which 5 drives the large gear 27. In the event that it is desired to propel the spindle at a relatively lower rate, the gear 30 is shifted downwardly to bring its teeth 33 into engagement with the clutch-teeth 35 formed 10 on the side of the large gear 27. This connection is in the nature of a positive clutch, there being no gear action between the teeth 33 and the teeth 35. When this latter connection has been established, the high speed 15 gear 29 is isolated and runs idly and the large gear 27 is in effect clutched directly to the sleeve 11 and hence directly to the spindle to rotate the latter at a relatively slow rate. It will be perceived, therefore, 20 that the momentum to be overcome by the friction clutches between the shaft 2 and the gear 4 is not in any wise affected by the speed of the large gear 27; irrespective of whether it is or is not being utilized for 25 driving the spindle and therefore that large gear 27 is never permitted to manifest the excessive fly-wheel momentums which have been exhibited in prior constructions wherein a large gear-wheel rotated in unison with 30 the spindle when the latter was operating at high speeds.

The manner in which this invention fulfills the other enumerated objectives whereby the user is enabled immediately to ascertain 35 the proper settings controlling the primary and the secondary speed-change devices will be best understood by referring to Figs. 2 and 3. The secondary speed-change device shown by Fig. 1 is controlled 40 by two independently operable levers 36 and 37. The lever 36 has a sleeve-like hub 38 journaled in an aperture through the side-wall of the casing 8 of the head and, at its inner end, carries a lever 39 projecting to 45 end in alignment with the spindle and pivotally carrying the shoe 32 that engages an annular groove 40 in the gear 30. By shifting the lever 36, therefore, the gear 30 may be placed either in its neutral position shown 50 by Fig. 1 or in either of its two operative positions above explained. The other hand-lever 37 has a shaft 41 journaled through the bore of the hub 38 of the first-mentioned lever 36 and it likewise has a lever 42 affixed 55 to its inner end and extending to terminate in alignment with the shaft 5 so that the yoke or shoe 17 pivoted to its remote end may be enabled to control the shifting of the gear 15 depending upon the actuation of 60 the lever 37.

By suitable manipulation of either one or both of the levers 36 and 37, there becomes available a series of speed changes derived from the change gears shown by Fig. 1; in 65 this case there being four different changes

available. These are termed the secondary changes and are relatively coarse.

In order to enable the user to determine the extent to which the above-mentioned speeds should be modified by manipulating 70 the primary speed box or motor, as the case may be, this invention proposes two indicating plates 43 and 44 together with means for causing these plates to be shifted in position; the one by the lever 36 and 75 the other by the lever 37. This may be accomplished most directly in the manner shown by the drawings; to-wit, by giving these plates an arc-like contour and affixing them directly to the levers. The one 80 plate is, as shown by Fig. 3 divided into four equal divisions representing the four speed ratios available directly from the secondary change gears. The other plate 44 has a single division equal in length to one 85 of the four divisions on the plate 43 and this single division is subdivided into as many sections as there are speeds available at the primary speed box or motor; each section bearing appropriate numbers as 90 shown and each section preferably has a pointer 45 directed towards the other plate 43. Arranged in column form on the other plate 43 are two sets of numbers; those in the first column indicating the drill sizes 95 and those in the adjacent column indicating the revolutions at which the drill should be operated. The vertical distances between the numbers in these two columns correspond to the spacing on the plate 44 representing the primary change speeds. By this 100 arrangement it is manifest that the user can immediately determine the proper adjustments of the machine without any mental effort. For example, should he have occasion to use drill #5 or a 5" diam. tool, he will shift the levers 36 and 37 until the plate 44 coincides with the division on plate 43 containing "5". When this is done, it 105 will be found that the second division (the one numbered 2) coincides in alignment with the "5" and the user thereupon learns that he should go to the rear of the machine or wherever else the primary lever is located and adjust it to its second position. Then the machine will rotate the spindle at 110 59 revolutions which is substantially the setting required for the particular drill in hand.

It will, therefore, be seen that this invention in a very simple and direct manner affords not only a notably convenient machine but likewise one characterized by a very pronounced elimination of many of the 115 troubles heretofore experienced with the friction clutches.

Without further analysis, the foregoing will so fully reveal the gist of this invention that others can, by applying current knowledge, readily adapt it for various utiliza- 120 125 130

tions by retaining one or more of the essential characteristics of either the generic or specific aspects of this invention, and, therefore, such adaptations should be, and 5 are intended to be, comprehended within the meaning and range of equivalency of the following claims:—

Having thus revealed this invention, I claim as new and desire to secure the following combinations and elements, or equivalents thereof, by Letters Patent of the United States:

1. A drilling-machine combining a power-driven member; a drill-supporting spindle; 15 a motion-reverser embodying friction-clutches deriving motion from said power-driven member; and a speed-change transmission intervening between said motion-reverser and said spindle for driving said 20 spindle at variable speeds, said transmission comprising in coaxial relation with said spindle a small gear for driving it rapidly and a large gear mounted to rotate independently of said spindle when it is 25 driven rapidly by said small gear but adapted to be clutched to said spindle to drive it slowly when said small gear is not being utilized to drive said spindle rapidly.

2. A radial-drill combining a horizontal 30 arm; a power-driven shaft horizontally journaled in said arm; a drill-head slidably mounted on said arm; a drill-supporting spindle vertically journaled in said drill-head; a motion-reverser of the friction 35 type arranged in said drill-head to derive motion directly from said horizontal shaft; a speed-change transmission intervening between said motion-reverser and said spindle, said transmission embodying a large and a 40 small gear coaxial with said spindle, the large gear being permanently driven at a low rate of speed and adapted to be clutched to said spindle to rotate it at a corresponding rate, said transmission also embodying 45 means for de-clutching said large gear from said spindle and causing it to be rotated rapidly by power driven through the small gear whereby the large gear may idle slowly while the spindle is rapidly rotating and the 50 clutches of the motion-reverser will be relieved from the necessity of overcoming excessive momentum in reversing the motion of the idling large gear.

3. A drilling-machine combining in serial 55 relation a power-driven shaft, a frictional motion-reverser, a speed-change mechanism and a drill-supporting spindle; the speed-change mechanism embodying a permanently driven large gear loosely journaled 60 in coaxial relation with said spindle, gearing for independently driving said spindle rapidly; and means for rendering said gearing inoperative and for clutching said large gear to said spindle to rotate it slowly.

4. A drilling-machine comprising a pow-

er-driven shaft; a frictional motion-reverser deriving motion therefrom; a drill-supporting spindle; a large gear loosely journaled about said spindle; a small gear coaxial with said spindle; transmission elements between 70 said motion-reverser for enabling said large and small gears to be driven; a clutch mechanism adapted to connect said large gear with said spindle for driving it slowly and to establish a dis-connection and cause said 75 spindle to be driven rapidly by said small gear and thereby relieve the frictional motion-reverser of the necessity of overcoming the inertia which would be possessed by the large gear if rotated at high spindle speeds. 80

5. A machine-tool combining a prime-mover and a tool-supporting member deriving motion therefrom; primary and secondary speed-change devices arranged serially between said prime-mover and said 85 tool-supporting member; levers for adjusting the speed imparted by the secondary speed-change devices; and index plates having their mutual relations determined by the positions of said levers, said index plates 90 being devised to indicate the adjustment to be given to the primary speed-change device for each relation of said levers to satisfy the speed requirements of the character of tool carried by said tool-supporting member. 95

6. A drilling-machine combining a prime-mover and a drill-spindle; a transmission there-between embodying a primary speed-change device located adjacent the prime-mover and a secondary speed-change device located adjacent the spindle; a pair of levers for determining the speed transmitted by the secondary speed-change device; two relatively movable index plates each having 100 its position determined by said levers respectively, said index plates being constructed to portray the correct adjustment of the primary speed-change device to satisfy the requirements of the size of drill 105 mounted on the spindle for each of the available relations between the said levers. 110

7. A drilling machine combining a prime-mover and a drill-spindle; a transmission therebetween embodying primary and secondary speed-change devices, said secondary speed-change device including a plurality of gear members located adjacent the drill-spindle and operatively connected therewith and adapted selectively to be engaged; two 120 gear-shifting levers for engaging said gears; an index-plate carried by one of said levers, said index-plate being divided into a plurality of divisions each of which is subdivided into a plurality of sections, each of said sections being marked to indicate a drill diameter and an efficient speed of rotation therefor; a second index-plate carried by the other of said levers adjacent said first 125 named index-plate, said second index-plate 130

having a single division equal in length to one of the divisions on said first index-plate and being subdivided into the same number of sub-divisions as the number of sections 5 into which the divisions of said first index-plate is divided, each of said sub-divisions bearing a number representing a possible position of adjustment of said primary speed change device, said two index-plates cooperating, after the secondary speed-change device 10 has been shifted, to indicate the posi-

tion of adjustment necessary in the primary speed-change device to effect a predetermined speed of rotation of the drill-spindle. In witness whereof, I hereunto subscribe 15 my name, as attested by the two subscribing witnesses.
